UNITED STATES PATENT OFFICE.

ALFRED ROESCH, OF BROOKLYN, NEW YORK, ASSIGNOR TO CHARLES J. TAGLIABUE MANUFACTURING CO., OF BROOKLYN, NEW YORK, A CORPORATION OF NEW YORK.

DESIGN FOR A BLOOD-PRESSURE GAGE.

53,023.

Specification for Design.

Patented Feb. 25, 1919.

Application filed June 30, 1917. Serial No. 178,038. Term of patent 14 years.

To all whom it may concern:

Be it known that I, ALFRED ROESCH, a citizen of the United States, and resident of the borough of Brooklyn, county of Kings, city and State of New York, have invented a new, original, and ornamental Design for Blood-Pressure Gages, of which the following is a specification.

In the accompanying drawings which show an example of my invention, Figure 1 is a front elevation of a blood pressure gage showing my new design; Fig. 2 is a side view; and Fig. 3 is a plan view thereof.

As shown in the drawings, the design comprises a cylindrical portion *a* from which depends a nipple *b* and a casing *c* which extends upwardly from the portion *a*. The side walls *d* of the casing *c* diverge upwardly from said cylindrical portion *a* and are connected at their outer ends by a curved

top wall *e*; the front and rear walls *f* and *g* of the casing are substantially parallel with each other, as shown in Fig. 2. The front wall *f* is provided with an opening *h* through which a scale *i* is visible; in the illustrated example, the side edges of the opening *h* are substantially parallel with the side walls *d*, while the upper edge of said opening follows the curve of the top wall *e*. The lower edge, in the illustrated example, comprises upwardly curved portions *h'* extending toward each other from the side edges and connected by a central downwardly curved portion *h''*, the whole edge having approximately the appearance of a double ogee curve.

I claim:

The ornamental design for a blood pressure gage, as shown and described.

ALFRED ROESCH.
